CAPTIVE BALLOON

Jean Letourneur, Versailles, France

Application November 23, 1932, Serial No. 644,054
In France November 27, 1931

3 Claims. (Cl. 244—4)

Captive balloons which are elongated so as to be stabilized in the wind are provided with fins attached to the rear of the body. These fins are constituted, in general, by air chambers, the outer 5 surface of which is made of an impermeable material and into which air is introduced automatically by means of one or more vents or scoops, placed suitably. The wind thus maintains a pressure therein under the influence of which the 10 exterior surface tends to acquire a sufficient rigidity for the fin to fulfill effectively its purpose.

Now it is known that the geometrical surfaces that it is possible to obtain with a fabric held taut by an interior pressure are very limited; it is essential that, under the action of said pressure, the surfaces be under tension at every point and in all directions around said point. If a compression should exist at any place the fabric would fold and the surface actually obtained would be 20 entirely different from that calculated. Now the difficulty which is encountered in the calculation of the surfaces having this property is such that, generally, one is restricted to the use of simple surfaces of revolution for which the above imperative condition is realized. If it is necessary to realize other forms, one is led to divide them into 25 sufficiently small elements for each of them to be considered as a part of a surface of revolution having this property. It is only necessary to 30 choose these surfaces judiciously so that at the lines joining the various elements there will not be objectionable reactions one on the other, which would produce serious deformations.

Further, to make the fins effective it is important that their lateral exterior surface should offer a great resistance to the wind; for this reason the fins are generally constituted by elements whose surfaces are joined by concave angles; these produce "furrows" maintained in place by interior 35 connections such as networks of cords, fabric partitions or the like which make the fin very effective.

But on the contrary when the balloon lies in the wind; that is to say is in the normal position, it is 40 necessary that the fin should offer to the wind the least possible resistance. It is known that one of the most favourable conditions for obtaining this result consists, on the one hand, in giving to the body offered to the wind, a surface convex towards 45 the front and on the other hand, in reducing the thickness of this body from the front to the rear in such a way that the streams of air shaped by the front part remain as far as possible tangential to the lateral exterior face of this body.

50 In accordance with the present invention an

inflatable fin for a captive balloon is composed of elements constituting sections of surfaces of revolution and is characterized by the fact that all of said elements are substantially tangential to two spaced apart enveloping imaginary surfaces which are developable and also symmetrical with respect to a plane passing through the axis of the balloon, and each of which includes a meridian of the body of the balloon, the radii of the bases of the individual sections decreasing towards the 10 rear of the fin.

It is well understood as to the line of junction of two of these elements that when there is not a common tangent plane at every point of the seam connecting them, the concave angle is maintained in place by a network of cords or a partition of fabric suitably pierced with large holes for 15 assuring a free circulation of air in the fin.

These fins are applicable to all captive balloons but their utilization is particularly advantageous 20 on the balloons with "lobes" in which the cross section on a plane perpendicular to the axis of the body envelope is, not a circumference, but a certain number of arcs of a circumference equal or not in size, the cords of which form a polygon, 25 with extensible sides or not. In such balloons which present otherwise and for certain purposes, particular advantages it is well evident that the surface comprised between two meridian furrows on which is to be inserted a fin is smaller than 30 that on which the same fin would be inserted on a body envelope having the shape of a body of revolution. Towards the rear moreover when the linear dimensions of the sections diminish, it 35 might be difficult to place a fin of constant thickness. On the contrary the use of fins of decreasing thickness inserted between two meridians of the envelope is easy, logical and advantageous.

The invention thus generally described is adapted to numerous particular applications to 40 which the protection of this patent application should naturally extend as well as to apparatus utilizing the same method and to their separate parts. Altogether it can be well understood with the aid of the following and with the attached 45 drawings which it is to be understood are given only by way of example.

Fig. 1 represents a lateral elevation and Fig. 2 a rear view of a fin constructed according to the 50 invention.

Fig. 3 is a section through the said fin on the plane shown at 3—3 on Fig. 1.

Figs. 4 and 5 show two further forms of fin in elevation and

Fig. 6 is an end view of Fig. 5.

The general form of the fin is similar to those which are ordinarily employed; its exterior contour is composed towards the front by an inclined cylindrical surface C connected at the rear with a surface of the general form of a toroid D. All the space between the envelope and this contoured surface, which hereafter will be designated by the term "horn" is filled with portions of cylinders of revolution, the radii of which decrease 10 towards the rear and which are defined as will be seen below.

To plan the fin, one commences by determining, by taking into account the volume of the balloon, its purpose, its form and so on, the general dimensions of the fin and in particular its length along the meridian of the contour of the body envelope and its maximum thickness. One can thus determine the axis of the "horn" which is composed for example of a line $a-b$ and a 20 circumferential arc $b-c$.

There is then considered a cylinder of revolution C around the line $a-b$ as axis, having for its diameter the thickness fixed. One determines then easily the intersection of this cylinder with the body envelope and in particular the point 1 traced on this envelope by the generatrix of the cylinder C situated in the plane passing through the axis $a-b$ and perpendicular to the projection plane.

It is then possible to trace the meridian 1-2 of the envelope passing through the point 1; this meridian is indicated in dotted lines on Fig. 1. On Fig. 2 there is shown the two meridians 1-2 and 1^1-2^1 symmetrical relatively to the projection plane.

Then the symmetrical cylindrical surfaces applied to the meridians 1-2, 1^1-2^1 and of which the generatrices are parallel to $a-b$ are considered. Hereafter these surfaces are called the "envelope surface of the fin".

It is evident that the generatrix 1-3 of the cylinder C is common to the envelope surface and to the cylinder C and that the two surfaces are tangential for the full length of this generatrix.

For determining the theoretical surface of the curved part D of the horn, one considers at every point of the arc $b-c$ a circle having its centre on $b-c$, the plane of which is perpendicular to $b-c$ and of which the diameter is equal to the distance separating the two meridians 1-2 and 1^1-2^1 on planes transverse to the longitudinal axis and including the successive points considered. Then the envelope surface of these circles is determined when the point describes the arc $b-c$. This surface which is attached tangentially to the cylinder C has generally the form of a toroid which is tangential to the envelope surface along the whole length of the two symmetrical arcs of circles projected from the arc $b-c$ on Fig. 1.

The horn is thus entirely determined.

A section of the fin is then made perpendicular to $a-b$ on a plane such as 4-5. The projection of the section of cylinder C is a circle c of which the diameter is equal to the maximum thickness. The projection of the intersection of the same plane with the envelope surface is composed of two symmetrical curves easily determined plotting points of which the projections are on the lines 6-7 and 6^1-7^1 . Then there is traced after the circle c a series of circles c^1, c^2, c^3 and so on all tangential to the curves 6-7, 6^1-7^1 and each intersecting the foregoing, for example by a constant angle, suitably chosen. These circles are considered as transverse sections of a series of

cylinders of revolution C^1, C^2, C^3 and so on having their generatrices parallel to $a-b$. It is evident that all these cylinders are tangential to the envelope surface according to generatrices projected on the axis of these cylinders.

It is sufficient to determine the intersection of these different cylinders on the one hand with the body envelope and on the other hand with the toroidal part of the horn in order that the fin is entirely defined.

In practice it would often be convenient to replace the theoretical toroidal surface of the horn by truncated cone elements of revolution connected successively by their bases and having as their total length a dimension at most equal to the available size of the material employed for the construction of the fin; in this latter case, these truncated cone elements are no longer theoretically but only practically tangential to the envelope surface. Further by the action of the interior pressure when the fin is inflated with air, the true surface would be very near the theoretical toroidal surface as long as the lengths of the truncated cone elements are very small.

It is well understood that in construction there should be disposed perpendicular to the plane of symmetry and at the bottom of the furrows, suitable connections, for example fabric partitions, so that these appear in the projection of the section according to the plane 4-5, the sizes of which partitions are constant for each of them; these partitions, which are represented in the projection at 8-9, 8^1-9^1 and so on are pierced with apertures so that the air can circulate freely through the whole of the fin.

Finally, a vent or scoop 10 suitably placed according to the inclination of the balloon in ascent permits the entry of the air for inflating the fin.

The fin thus constructed is evidently of decreasing thickness; Fig. 3 shows a section on the plane of line 3-3 of Fig. 1 parallel to the axis of the body envelope; further it fulfils the conditions of the principle claimed; it is composed of elements of surfaces of revolution; all these elements are tangential to an imaginary surface, in this case cylindrical, including two meridians of the envelope. Further by arranging the maximum thickness and the angle according to which the circles c^1, c^2, c^3 intersect, one can vary as desired its thickness and the number of furrows and thus within certain limits its effectiveness and resistance in the wind.

Instead of taking a line parallel to $a-b$ for the direction of the generatrix of the envelope surface, one could take any other direction parallel to the plane of symmetry, for example a perpendicular to the axis of the body envelope. In the latter case the front part of the horn would no longer be a cylinder but a substantially conical surface and the furrows SS would be vertical as shown on Fig. 4 which represents the form of a fin thus realized.

Figs. 5 and 6 represent another embodiment in which the envelope surface is no longer a cylinder but composed of conical surfaces containing as before two symmetrical meridians of the envelope, and having for their apex a point S which in the example here described is situated in the plane of symmetry, on the vertical of the front of the envelope and in an extension of the line $a-b$ which is the axis of the front part of the horn. Further, it is supposed here that the body envelope would not have the form of a body of

revolution but would be composed of six equal lobes.

The points 21 and 21¹ are determined as before, symmetrically relatively to the vertical plane of projection, and they correspond on the envelope to the maximum given thickness for the fin. The meridians of the envelope passing through the points 21 and 21¹ are determined and the envelope surface composed of two conical sheets having for their apex the point S and which meet the meridians 21—22, 21¹—22¹, considered.

The horn is composed at the front by a truncated cone of revolution T, the axis of which is in the plane of symmetry, the apex of which is at S and of which a generatrix passes through the point 21, also, at the rear, by a surface of the general form of a toroid D, determined as in the preceding example with the single difference practically that instead of considering the parallels to $a-b$ lines concurrent at S are considered. This surface is evidently tangential to the envelope surface for the whole length of the symmetrical circular arcs projected on the plane of symmetry along $b-c$.

The space comprised between the envelope and the horn is entirely filled by portions of truncated cones of revolution T¹, T², T³ and so on with apex S, tangential to the envelope surface, for all the length of the generatrices projected on the axes of the cones. The sections t t^1 , t^2 , t^3 and so on, of the truncated cones T, T¹, T², T³ and so on, intersect on suitably chosen chords; for example the chord common to the sections of the cone T and T¹ is seen from the centre of the section t at a certain angle which is the same for similar sections t^1 , t^2 and so on.

It is sufficient then to determine the intersection of these different conical surfaces, on the one hand with the surface of the body envelope and on the other hand with the toroidal surface of the horn for the fin to be entirely fixed. In practice one would often replace the theoretical toroidal surface of the horn by a series of elements of truncated cones of revolution connected together by their successive bases. In this case the truncated cone elements would not be theoretically but only substantially tangential to the envelope surface. Further, under the action of interior pressure when the fin is inflated by the air, the actual surface would be near to the theoretical toroidal surface as long as the length of these truncated cone elements was very small.

Here again, the furrows would be maintained in place by partitions of fabric pierced with large openings perpendicular to the plane of symmetry; these partitions are here trapezoidal, they would be seamed to the edges of the sheets corresponding to the conical surfaces T, T¹, T² and so on. A valve 30 placed suitably permits the inflow of air which inflates the fin in ascent.

The fin thus constituted is evidently of decreasing thickness; further, it fulfils the conditions of the principle claimed; it is composed of elements of surfaces of revolution and all the elements are tangential to a developable surface, conical in this case, which contains two meridians of the envelope. Further, the thickness of this fin diminishes away from the envelope and the more rapidly the closer the common apex S of the conical surfaces has been taken to the en-

velope; one can thus diminish its resistance in the air while maintaining the total surface and the furrows and thus its effectiveness.

It is obvious that the examples given above are only indicated in order to make the invention understood and to show the diversity of its possible applications; further, they do in no case limit the arrangements which can be realized by the invention.

What I claim and desire to secure by Letters 10 Patent of the United States of America is:—

1. An inflatable fin for a captive balloon comprising a plurality of elements constituting sections of surfaces of revolution and an inflatable element extending along the outer edge of the 15 fin and to which each of the individual sections is connected, the said plurality of elements being arranged substantially tangential to two spaced apart enveloping imaginary surfaces which are developable and also symmetrical with respect to a plane passing through the axis of the balloon and each of which includes a meridian of the 20 body of the balloon, the radii of the bases of the individual sections decreasing towards the rear of the fin.

2. An inflatable fin for a captive balloon comprising a plurality of elements constituting sections of surfaces of revolution and an inflatable element extending along the outer edge of the fin, said inflatable element having a conical portion and being curved to the shape of a horn, the said plurality of elements being arranged substantially tangential to two spaced apart enveloping imaginary surfaces which are developable and also symmetrical with respect to a plane 30 passing through the axis of the balloon and each of which includes a meridian of the body of the balloon, whilst the radii of the bases of the individual sections decrease towards the rear of the fin, and said sections have in common with said horn-shaped element and with each of the two spaced apart enveloping imaginary surfaces a common tangent plane, the said horn-shaped element being connected to the balloon surface between the two meridians defining the said 35 spaced apart enveloping imaginary surfaces.

3. An inflatable fin for a captive balloon comprising a plurality of elements constituting sections of surfaces of revolution and an inflatable element extending along the outer edge of the fin, said inflatable element being partly cylindrical and partly conical and curved to the shape of a horn, the said plurality of elements being arranged substantially tangential to two spaced apart enveloping imaginary surfaces which are developable and also symmetrical with respect to a plane passing through the axis of the balloon and each of which includes a meridian of the body of the balloon, whilst the radii of the bases of the individual sections decrease towards the rear of the fin, and said sections have in common with said horn-shaped element and with each of the two spaced apart enveloping imaginary surfaces a common tangent plane, one end of the cylindrical portion and one end of the conical portion of the said horn-shaped element being connected to the balloon surface between the two meridians defining the said spaced apart enveloping imaginary surfaces.
